Primary Examiner — Catherine R Oliver-Garcia*(74) Attorney, Agent, or Firm* — Boyle Fredrickson S.C.(57) **CLAIM**

The ornamental design for a fish hook, as shown and described.

DESCRIPTION

FIG. 1 is a top, front and right side isometric view of a fish hook according to the present invention attachable to a fishing line containing a knot;

FIG. 2 is a right side elevation view of the fish hook of FIG. 1.

FIG. 3 is a left side elevation view of the fish hook of FIG. 1;

FIG. 4 is a front elevation view of the fish hook of FIG. 1; FIG. 5 is a rear elevation view of the fish hook of FIG. 1; FIG. 6 is a top plan view of the fish hook of FIG. 1; and, FIG. 7 is a bottom plan view of the fish hook of FIG. 1. The broken lines in the figures depict portions of the fish hook that form no part of the claimed design.
